UNITED STATES PATENT OFFICE.

ELLA MATILDA YARRINGTON AND THOMAS HALL, OF NEW YORK, N. Y.

DESIGN FOR A CHILD'S NAPKIN.

SPECIFICATION forming part of Design No. 28,778, dated May 31, 1898.

Application filed June 11, 1897. Serial No. 640,387. Term of patent 14 years.

To all whom it may concern:

Be it known that we, ELLA MATILDA YARRINGTON and THOMAS HALL, citizens of the United States, residing at New York city, in 5 the county and State of New York, have invented and produced a new and original Design for Child's Napkin, of which the following is a specification, reference being had to the accompanying drawings, forming a part thereof.

In the drawings, Figure 1 shows the napkin in side elevation. Fig. 2 is a front view of the same, and Fig. 3 is a top view.

The leading feature of our invention consists in the shape or configuration of the article—namely, the approximate V shape in front elevation and the continuous curved line shown in the side elevation forming the outline of the article.

As shown in Fig. 2, there is a pendent por-

tion A of V shape, the walls of which rise at an angle, these walls being pierced with limb-openings E E'. The upper part of the napkin is approximately round in plan view, as shown in Fig. 3, and there is a curvature from this waist portion B D down to the V portion. The napkin in side elevation, as shown in Fig. 1, presents an outline of a continuous curve from waist-line to waist-line, as indicated by the position of the lines D, A, and C.

What we claim is—

The design for a child's napkin as herein shown and described.

In testimony whereof we affix our signatures in presence of two witnesses.

ELLA MATILDA YARRINGTON.

THOS. HALL.

Witnesses:

JOHN A. TENNANT,
A. J. DICKSON.
